UNITED STATES PATENT OFFICE

91,022

DESIGN FOR A BOOK TROUGH OR SIMILAR ARTICLE

Herman E. De Vries, New York, N. Y., assignor to H. T. Cushman Mfg. Co., North Bennington, Vt.

Application May 31, 1933. Serial No. 48,250

Term of patent 3½ years

To all whom it may concern:

Be it known that I, HERMAN E. DE VRIES, a citizen of the United States, residing at New York city, in the county and State of New York, have invented a new, original, and ornamental Design for a Book Trough or Similar Article, of which the following is a specification, reference being had to the accompanying drawing, forming a part thereof.

The figure is a perspective view of a book trough showing my design.

I claim:

The ornamental design for a book trough or similar article, as shown.

HERMAN E. DE VRIES.
